UNITED STATES PATENT OFFICE.

JOHN RUTHERFORD, JR., AND THOMAS F. BAKER, OF ALBANY, NEW YORK,
ASSIGNORS TO THE EMBOSSED COMPANY, OF ALBANY, NEW YORK, A COR-
PORATION OF NEW YORK.

GAME.

1,387,946.

Specification of Letters Patent. Patented Aug. 16, 1921.

Application filed November 6, 1920. Serial No. 422,325.

To all whom it may concern:

Be it known that we, JOHN RUTHERFORD, Jr., and THOMAS F. BAKER, both citizens of the United States of America, both residing at Albany, in the county of Albany and State of New York, have invented certain new and useful Improvements in Games, of which the following is a full, clear, and exact description.

10 This invention relates to games of the type in which an object is batted through the air, more particularly the type in which the object to be batted is elongated in form, with pointed ends. In some localities such an object is known as a "trigger," in others it is called a "cat," and doubtless has other names in other places. The object of the invention is to provide improved implements for games of the class referred to, introducing novel 20 features which will make the implements more attractive and will materially increase the interest to the players. To this and other ends the invention consists in the novel features and parts hereinafter described.

25 One form of the invention is illustrated in the accompanying drawing, in which—

Figure 1 shows the "trigger" or "cat" in perspective.

Fig. 2 shows the bat or paddle, on a 30 smaller scale.

Fig. 3 is a side view of the trigger, with the bat in section in the position in which it is about to strike the trigger to flip the latter into the air.

35 The trigger shown at 10 is a short block, preferably wood, square or of other polygonal cross section. The ends of the trigger are tapered, and terminate in rounded or bulbous tips, 11, preferably spherical. It is 40 desirable to have the tips composed of or covered with rubber. In playing, the trigger rests on the ground on one of its faces, as in Fig. 3, and is struck a quick blow on the end with the bat 12, thus flipping the trigger up into the air so that it can be struck with the bat and be driven forward. This method of batting a trigger is common and well known.

45 As stated, the trigger is polygonal in cross section, preferably square, so that if it is lying on the ground at least one face will be uppermost. The several faces are painted or stained in different colors, as green, red, blue and white, and they may also bear other 55 means of identification, as numbers or let-

ters, or preferably, spots or pips, like dominoes. In the present instance spots 13 are used, the several faces having different numbers of spots, as one, two, three and four, respectively.

60 The bat shown at 12 is a stout paddle, having on one or both faces spaced cross bands or stripes, 14, 15, 16, 17, which may be colored or numbered in correspondence with the colored or numbered faces of the trigger. 65 In the present instance the bands are indicated as green, red, blue and white, respectively. In general the bands on the bat and the faces of the trigger should be the same in number, and should correspond in color. 70

75 The games and variations thereof that can be played with the two implements or diners shown are almost endless in number, from the most simple form of "old cat" or "tip-cat" to more complicated games, as will be readily understood, and it is expected that the players will in this respect be guided largely by their own ideas. One method of play, very interesting and exciting to small boys, is as follows:

80 On the ground or pavement a circle is drawn, near which the batter takes his position; the other players, or fielders, (any number) taking position in front of him at suitable distances. One of the fielders, designated the pitcher, tosses the trigger toward the circle. If it comes to rest inside of or overlapping the circle, the batsman is "out" and retires to the field, the pitcher becoming 85 batsman and the next fielder, in a predetermined order, becoming pitcher. As the pitcher tosses the trigger to the circle he names a color. If this color in the trigger comes up, the batsman is out, whether or not the trigger lands in the circle. If another 90 color comes up (the trigger landing wholly outside the circle) the batsman in flipping and batting the trigger must hold the bat with his forefinger in contact with the designated color, and he is allowed as many 95 "strikes" or tries as the number of spots on the uppermost face. Thus, if the pitcher, as he delivers the trigger, calls "white" but "red" comes up, the batsman gets four tries but must hold the bat with his forefinger on 100 the red band or stripe. If the batted trigger is caught on the fly by a fielder the batter is out. If not caught, or if a "grounder" is 105 batted, the batsman is out if he cannot run to a designated base and back to the circle 110

before the trigger is fielded and thrown in or placed in the circle. If the trigger has an odd number of flat faces the pitcher has two chances (out of three, or five, etc., as the case may be) of the color named coming up, and the batter may have a greater number of strikes, say the sum of the pips on the two faces, or may have a choice as to color or as to number of strikes.

10 Obviously, the game described can be varied almost indefinitely, and we do not regard our invention as limited to any particular game, or method of use or play, or to any particular rules, or any particular method of scoring, or to any particular use or method of use.

15 The rounded or enlarged ends of the trigger are very desirable features, as they greatly increase the ease of flipping the device into the air, the enlargement forming a sort of pivot on which the trigger turns as it strikes the grounder under the impact of the bat. The enlargements also practically eliminate the danger of any serious injury 20 to a fielder if he is struck by the trigger, a small bruise being about the worst that can happen, whereas the sharp point of a trigger of the old type sometimes inflicts a deep cut or tear.

25 It is to be understood that the invention is not limited to the specific features herein described but can be embodied in other forms without departure from its spirit.

We claim:

30 1. A game outfit comprising a trigger of polygonal cross section, and a bat, the faces

on the trigger and spaced areas of the bat being marked to correspond, whereby the faces of the trigger are identified with or correspond to particular areas on the bat, 40 and vice versa.

2. A game outfit as set forth in claim 1, in which at least one face of the trigger is numbered.

3. A game outfit as set forth in claim 1, 45 in which a plurality of the faces of the trigger are numbered, with different numbers on different faces.

4. A game outfit as set forth in claim 1, 50 in which the faces of the trigger are numbered by means of spots, with different numbers of spots on different faces.

5. A game outfit comprising a trigger of polygonal cross section, and a bat, the faces 55 of the trigger being colored in different colors and the bat having spaced areas colored to correspond with the colored trigger faces.

6. A game outfit as set forth in claim 5, 60 in which the faces of the trigger are also marked with different numbers of spots.

7. A game device consisting of an elongated member of polygonal cross section, having flat faces differently colored and bearing spots in different numbers, and having sharply tapering ends terminating in 65 relatively small substantially spherical enlargements.

In testimony whereof we hereto affix our signatures.

JOHN RUTHERFORD, JR.
THOMAS F. BAKER.
